UNITED STATES PATENT OFFICE

ALEXANDER KONOFE, OF NEW YORK, N. Y., ASSIGNOR TO MARKON MANUFACTURING CO. INC., OF NEW YORK, N. Y., A CORPORATION OF NEW YORK

METHOD OF PRODUCING DOLL EYES

Application filed October 12, 1927. Serial No. 225,693.

This invention relates to an improvement in doll eyes, particularly to the end that the eyelid-forming portion of the eye, as well as the eyelashes carried by the eye shall bear such relation to the eye opening of the doll head as to present a highly human-like and pleasing appearance.

A more specific purpose is to so shape the edge contour of the eyelid-forming portion of the eye that when the eye is in its "open" position within the doll head the edge portion of the eyelid will suitably conform to the curvature of the eye opening of the head, also that an eyelash member attached at and extending along the edge of the eyelid-forming portion will likewise conform in general shape and contour to the adjacent curved edge of the head opening.

A further object is to provide a multiple blank from which the eyes are to be formed and to so color parts of the blank that when the eyes are shaped up therefrom the eyelid-forming portion will have a lower edge contour as above mentioned.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:—

Fig. 1 is a front elevational view of a doll eye constructed in accordance with this invention.

Fig. 2 is a side elevational view of the structure seen in Fig. 1.

Fig. 3 is a view similar to that seen in Fig. 1, the eye being here shown however as looking directly forwardly, rather than diagonally downwardly as in the previous figures, and being shown in association with a portion of a doll head, and

Fig. 4 is a plan view of a portion of a mul-

tiple blank from which the eyes are to be cut and shaped up.

Referring to the drawings for describing in detail the structure illustrated therein, the reference character L indicates the eye body this being usually, though not necessarily, in the form of a hollow shell of sheet material, such as celluloid, sheet metal or the like. It might in some instances be made of glass, or be of solid molded or other appropriate material.

At a proper locality visible upon the outer surface of the eye is the iris G, and above the iris is the eyelid-forming portion H.

The eyelid-forming portion H may consist merely of color painted, printed, or otherwise applied to the material of the body L, or it may consist of a separate piece of sheet material attached to or arranged as a continuation of the body. It is of flesh color approximating the color of the outer surface of the doll head, whereas the surface portion of the body below the lower edge of the eyelid, outside of the iris, is of an appropriately whitish color to represent the white portion of the human eye.

The reference character 1 indicates a portion of a doll head having the eye opening as 2 therethrough, the eye L being visible through said opening, in the usual manner. The opening 2 may be of any desired shape suitably corresponding to the eye opening in a human head, it being however formed with an upwardly curved upper edge wall as 3 behind which the eyelid-forming portion H of the eye is intended to roll when the eye moves to "open" position. It has been discovered that in order to more closely resemble the human eye in appearance and operation the lower edge as 4 of the eyelid should closely proximate the curvature of the edge wall 3, and it is therefore a particular purpose of the present invention to so design the eyelid H that in use it will have its lower edge 4 conform in curvature substantially to the curvature of the upper wall 3 of the head opening.

The importance of this improvement, from a practical and artistic standpoint, is most apparent in eye structures which carry

eyelashes thereon to move with the eye into and out of open position. In the drawing therefore the eye is shown to be provided with an eyelash-forming part or member 5 arranged to extend along the lower edge 4 of the eyelid H and to thus prominently define said edge and effectively separate the eyelid portion of the eye from the iris and white portions of the eye, said eyelash-forming member being thus of course made to extend along the curved line defined by the edge of the eyelid as above described, and thus making the eyelash member to come into substantial contact throughout its length with the edge surface of the wall 3 of the head opening when the eye is open. A wide-open, life-like, pleasing and attractive appearance is thus presented, as compared with the half closed, dull and listless appearance present in dolls as heretofore manufactured where the longitudinal curvature of the eyelash member is on a less radius than the curvature of the upper wall of the head opening.

The eyelash member 5 may be connected with the body L in any appropriate manner, but for the purpose of illustration is shown to be attached by being inserted within a slot or slit as 6 provided in the eye shell, after the manner shown and described in the pending application of Alexander Konoff, Serial No. 148,135, the slot or slit 6 being at the lower edge of the eyelid-forming portion H and extending in the same curved direction as said lower edge so as to separate the eyelid-forming portion from the iris and white portions of the eye.

In instances where the eye as hereinabove is formed from a flat blank of sheet material the coloring of the material is preferably done before the material is shaped up into its spherical or semispherical form, as for instance by printing or lithographing in color upon a sheet of suitable material, the eye blanks being duplicated a multiplicity of times upon the sheet, as indicated in Fig. 4. A sheet of the type as indicated in Fig. 4 may be run through a machine and the eye pictures thereon be cut out and stamped or pressed up into semispherical shape, and concerning this blank it is particularly desired to point out that each eye is defined by a circle as 7 within which is printed the iris, the upper part of the surface expanse within the circle being colored to represent the eyelid portion H and the lower part containing the iris and being otherwise of a whitish color to represent the white portion as 8 of the eye. The line of division between the portions H and 8 extends straight across the circle from opposite sides as at 9-9 but its central portion is curved upwardly about the iris as at 10. This line will define in the completed eye the lower edge of the eyelid. An eye lash member as 5 may be attached along said line, as by means of a slot

or otherwise, and the curvature of said line is such that when the blank is shaped up in its final semispherical form said curvature will correspond with the curvature of the wall 3 of the head opening.

It will be understood that the eye may be mounted in any suitable manner within the doll head for oscillatory movement into open and closed position, the drawing indicating for this purpose a suitable cross rod as 11 upon which two eyes may be mounted, and said rod being attached to the head by an appropriate bracket as 12.

As many changes could be made in this construction without departing from the scope of the invention, as defined in the following claim, it is intended that all matter contained in the above description, or shown in the accompanying drawings, shall be interpreted as illustrative only and not in a limiting sense.

Having thus described my invention, what I claim as new and desire to secure by Letters Patent is:—

The herein described method of producing an artificial eye ball for use within the eye opening of a doll head, and having an eye lid simulating portion the lower edge of which will register in curvature with the upper edge of the eye opening of the head, which method consists in providing a substantially flat sheet of material pressable into eye ball form, providing the representation of an iris upon said sheet, providing upon said sheet the representation of the white of an eye adjacent said iris, providing also upon the sheet the representation of an eye lid having its lower edge curved above the iris upon a curvature which is different from the curvature of the upper edge wall of the eye opening of the doll head, and then pressing the sheet to bring it into eye ball form and to at the same time change the curvature of the lower edge of the eye lid to correspond with the curvature of the upper edge of the eye opening of the doll head.

In testimony whereof I affix my signature.
ALEXANDER KONOFF.
